WEATHERPROOF SOCKET

Clinton Bateholts, Hoosick Falls, N. Y., assignor
to Specialty Insulation Manufacturing Com-
pany, Inc., Hoosick Falls, N. Y., a corporation
of New York

Application May 4, 1932, Serial No. 609,067

2 Claims. (Cl. 173—358)

This invention relates to improvements in weather-proof sockets. More particularly it relates to sockets for receiving electric light bulbs, cord plugs and the like, and especially to the weather-proof class of such sockets which are suitable for use out-of-doors, in connection with sign illumination, out-door decorations, and for other lighting or power connections.

Hitherto weather-proof sockets of this general description have been made of condensation material molded around the usual metallic sheet metal shell which is formed with a screw thread to receive the lamp. The shell wall constitutes one electric terminal; and the inner 5 end of the shell is closed by a porcelain insulating disk in the midst of which is set the brass pin which constitutes the other electric terminal. In the weather-proof type of socket with which the invention is concerned, these interior 10 terminals are each at the inner end of an insulated wire, to which each is firmly connected by solder; and these wires lead out through the base of the molded housing and extend for a few inches for convenience of connection to a 15 pair of feed wires by tapping those wires wherever required. The socket and its lamp will then be supported by suspension from the feed wires.

The invention relates to the combining of the metallic shell with the molded insulating 20 casing which houses it. Hitherto, in the making of such sockets, it has been customary to have a mold into which the shell unit would be set, having been previously prepared with wires attached, and being screwed upon a stud in the mold, and the wires being brought out through the top of the mold cavity; and the 25 molded compound would then be filled in around the shell, making an operation that would have to be executed piece by piece and which therefore was slow and relatively quite expensive as compared with modern molding practice in general.

Efforts to improve upon this have been made by molding a socket body as a separate article, 30 which would be a distinct advantage if successful, but it has been a problem to provide so that the inserted metal shell, in an assembled unit, would be held securely against relative rotation during use, and so that the union between them 35 would be permanently weather-proof.

It is among the objects of the invention to provide a combination by which a standard metallic shell may be positively and effectively locked within a separately molded socket body 40 or housing, so as to be permanently secure both

against being pulled out from the molded socket and against rotating therein (turning with the lamp base when the lamp is to be put in or taken out), and permanently tight against entrance of moisture.

Another object is to provide so that a complete socket unit may be assembled quickly and economically, as regards material and labor costs of manufacture.

And at the same time the completed unit provided by the invention must be fully as durable as the best molded prior devices of the sort, and as permanently strong, weather-proof and efficient.

The invention attains these objects and results by performing the molding operation on the socket body or housing independently of the shell. Consequently these housings can be made complete, each as a separate article, at very low cost, by molding them in gangs or 10 batches according to molding methods already known. The housing thus made has a pair of holes for the conductor wires to pass loosely through later when the metallic shell is inserted. The latter, which may be the usual 15 standard metallic shell, fits nicely into the hollow of the housing. A suitable synthetic water-proof composition is put into the bottom of the housing to seal said holes around the conductors 20 and to fill the lower space between the shell and housing. The shell being then pressed into place, the composition distributes itself, filling the necessary spaces, and in due course of time 25 becomes solidified. Without waiting for the solidification, the shell may be made permanently secure in its position by denting its sheet 30 metal wall outward at one or more points, opposite one or more cavities which were prepared for this purpose in the interior face of the housing. Although the dents are made through 35 the screw thread of the shell, into which thread the lamp base has to enter, they do not interfere with its reception, for they are dented toward the other side of the screw metal from that on which the lamp is received. This fastening means becomes operative as a lug, which locks the shell against escape from the housing 40 and against rotation therein. Also, by coaction with the solidified distributed composition, it inhibits looseness or other like cause for commercial criticism of the product.

However, the deformation of the shell walls need only be relatively small, and thus they do not affect in the slightest the ability of the shell to receive a lamp base or electric plug in the same character- 45

teristic manner as do the present electric sockets.

By virtue of the invention each of the parts is therefore free to be made in the most economical way; and a completed socket is made by a simple and quick assembling operation, which leaves the parts locked together, mechanically; with a plastic body sealing the holes and autogenously becoming hard.

10 It is intended that the patent shall cover, by suitable expression in the appended claims, whatever features of patentable novelty exist in the invention disclosed.

In the accompanying drawing:

15 Figure 1 is an elevation of a series of my improved sockets connected for use;

Figure 2 is an elevation, in medial section, through the molded housing of a socket similar to those of Figure 1;

20 Figure 3 is an elevation, in medial section through a completed socket, except that the wire conductors and the greater part of the metallic shell are left intact; and

Figure 4 is an enlargement of a fragment of Figure 3.

25 Referring to the drawing, three of my improved socket-assemblies are seen in Figure 1, as they may be connected in parallel to the feed wires 10, for use in connection with an out-of-doors illuminating scheme where they may safely be exposed, whether to rain, to hot rays of the sun, or to rigors of wintry weather,—weather-proof as regards all natural temperature and moisture conditions.

30 The socket housing 12, seen in detail in Figures 2, 3, is made by molding from any suitable composition material, such as phenolic condensation products, which is weather-proof and which also is an excellent insulator. The housing 12 which roughly is of cup shape, may be formed with two openings 14, 14, in its bottom or base end, which accommodate the insulated wire conductors 16, 16. These conductors are threaded through after being soldered as at 17 35 to the proper terminals on the standard type of metallic shell insert 18.

35 According to the invention, the molded body 12 has its cup shaped hollow 20, seen in Figure 2, of size to receive the shell 18 with nice fit around the side walls as seen in Figure 3, with a space below the insert, in the bottom part of the cup, through which space the conductors 16, 16 extend to their respective openings 14, 14 leading out of the unit. The body 12 is 40 molded into a shape providing one or more small abrupt recesses 22 interiorly of its side walls, well up toward its mouth. In the drawing four such recesses 22 are illustrated, but, obviously, a less or greater number may be provided, as desired. Thus formed, the molded housing 12 is ready to receive its insert 18, whose attached conductors 16 are at that time threaded through the openings 14 each of which is slightly larger in diameter than one of the conductors. A small amount of a viscous synthetic sealing composition 15 having been put 45 into the bottom of the cup body 12, all space remaining, around the conductors within the housing and in the holes 14, is filled thereby as the shell insert 18 moves into the hollow of the housing 12 and its leading end portion 19, which consists of a porcelain disk, becomes pushed into the plastic sealing medium 15, expressing it into all small spaces which need sealing, and holding the inner end of the brass

shell 18 steady within the housing when the sealing medium has hardened.

5 While any suitable sealing composition may be used for this purpose, I have found it satisfactory to employ the molding material disclosed in Patents 1,251,862 and 1,251,863 of January 1, 1918, granted on application of William W. Carter, a composition which is commonly characterized as a synthetic rubber substitute. When used for the purpose herein stated the composition is made so that it will 10 mold in a softer degree than the usual hard products and is solidified by the application of heat at the time the metal shell is forced into the molded housing.

15 My invention contemplates the reinforcing of the union by providing positive mechanical engagement or locking of the shell against movement relative to its housing member 12. This may be accomplished simply, quickly and economically by denting points on the shell walls 20 outward into the cavity recesses 22 of the housing 12. Said recesses are located near the mouth of the socket, and the shell walls conveniently may be deformed into them, by local expansion 25 as at 23 in Figure 3, without destroying the utility of the shell threads for receiving a lamp base, or the like. In fact a very small spreading of shell walls into a pair of such recesses at 30 opposite locations is sufficient to lock the shell effectively and permanently against rotatory movement, and also against being pulled axially out of the molded body 12. If preferred, the metal at 23 may be semi-punched and a tongue 35 of the metal bent outward into the recess 22. In either case this local expanding from the 40 midst of the threads sets portions of the shell directly against abutments, viz, against those recess walls which are toward the mouth of the casing, and against the side walls of each 45 recess. The shell and sealing medium thus become immobile within the housing,—unwithdrawable, and with no possible looseness or play, as the base of the shell came into superficial contact with the sealing medium when the shell was 50 pressed into it. In this position the sealing medium coats with the lug as a barrier to prevent rocking of the shell within the housing, and so makes the assembly perfectly and 55 permanently tight.

50 The invention thus provides for molding socket housings into which standard screw shells can be inserted, both housings and shells being made, and the two put together, on principles of mass production; with economies in production, with standard efficiency, and with permanent weather-proof durability.

55 I claim as my invention:

1. A socket for electrical connection, comprising a molded open-mouthed housing cup; and a terminal-carrying, open-mouthed, metallic screw shell housed by and interlocked with said housing; the interlocking being characterized by this, that a solidified plastic insulating composition is contained within the cup base of the 60 housing, extending under the bottom of the shell; that the base part of the shell is imperforate and is embedded in said composition; that the housing wall has a recess in its 65 interior face at a location opposite a screw part 70 of the shell; that said recess has walls which afford abrupt obstacles in direction toward the mouth of the housing and in directions around the shell; and that a part of the metallic shell, in the midst of the screw portion thereof, stands 75

abruptly protruded into said recess, and therein stands engaged with that wall of the recess which is toward the mouth of the housing, the axial distance, from the said recess-wall-ob-
5 stacle which is toward the mouth to that part of the composition against which the shell-base is embedded, being equal to the axial distance from the abutting face of said shell-base to the engaged face of said protruded part of shell,
10 whereby the shell, being simultaneously engaged both with the wall and the basal embedding composition, is held rigid in the housing.

2. A socket for electrical connection, comprising an insulating cup with a bi-terminal
15 metallic shell insert, conductor wires from the insert through holes in the cup-bottom, and a sealing medium in the cup-bottom facing the insert, the whole providing in the cup two op-
positely-facing obstruction-abutments, one of
20 which abutments is the cup's bottom with said

sealing medium facing the insert, on which a substantial area of the bottom part of the insert is engaged, there being means obstructing flow of sealing medium to the interior of the metallic shell; and the other of which abutments is 5 in a wall of the cup, there being a lateral recess in the cup's wall, open to the interior of the cup, and that wall of this recess which is toward the mouth of the cup constituting the abutment last mentioned; there being a part 10 of the shell-insert wall protruding laterally into engagement with said recess-wall, whereby mouthward movement of the insert is obstructed; and the axial distance between the two said abutments being equal to the axial distance be- 15 tween the two said parts of the insert, whereby the two said engagements of insert with cup are simultaneous.

CLINTON BATEHOLTS.
